United States Patent Office

Des. 203,754

Patented Feb. 15, 1966

203,754

PRACTICE-PUTTING TARGET

Harry Ganger, 168 S. Maryland Ave., Atlantic City, N.J.

Filed Apr. 7, 1965, Ser. No. 84,650

Term of patent 14 years

(Cl. D34—5)

FIG. 1

FIG. 2

FIG. 3

FIG. 4

FIG. 5

FIGURE 1 is a front perspective view of a practice-putting target showing my new design;

FIGURE 2 is a top plan view of the device of FIGURE 1;

FIGURE 3 is a rear elevational view of the device of FIGURE 1;

FIGURE 4 is a side elevational view of the device of FIGURE 1, both sides being identical; and

FIGURE 5 is a front elevational view of the device of FIGURE 1.

I claim:

The ornamental design for a golf putting target, as shown and described.
